SHELF RACK

Louis E. Pastorius III and Marion A. Caiaccia,
Pittsburgh, Pa.

Application April 11, 1951, Serial No. 220,442

8 Claims. (Cl. 211—41)

This invention relates generally to new and useful improvements in shelf racks and more particularly to a portable shelf rack for use in restaurants, hospitals and the like.

The shelf rack comprising this invention may be employed for supporting sterile articles and it can be provided with casters to make the same portable. Again the shelves of the racks may be slotted to provide guides for receiving and supporting trays, slides or other similar members in uniform vertical alignment. Such devices are particularly advantageous for use in large restaurants of the help yourself or cafeteria style wherein the patrons obtain a tray and then proceed with the same to select their food.

Another advantage of this invention is the provision of a tray that may be completely disassembled and stored or shipped as a relatively flat package.

Another advantage of this invention is the provision of a shelf rack wherein each part is separable and may permit the same to be disassembled for cleaning purposes.

Another advantage of this invention is the provision of a shelf rack that may be assembled or disassembled without the use of tools but merely by the means of thumb screws.

Other objects and advantages appear hereinafter in the following description and claims.

The accompanying drawings show, for the purpose of exemplification without limiting the invention or claims thereto, certain practical embodiments of the invention wherein:

Fig. 1 is an isometric view of this invention as applied to a portable tray rack.

Fig. 2 is an isometric view of one of the frames employed in each of the shelves of the tray rack as shown in Fig. 1.

Fig. 3 is a view in elevation of one of the angle posts members showing the inside of the angle, four of which posts provide a set of supports for a series of shelf racks.

Fig. 4 is a sectional view taken on the line 4—4 of Fig. 3 showing the angular post member shown in Fig. 3 having a set screw in the brace thereof.

Fig. 5 is an isometric view of one of the plate members slotted to receive trays, with parts broken away.

Fig. 6 is a sectional view taken through one of the shelves of the slotted rack for supporting a series of trays.

Fig. 7 is a detailed isometric view of the underside of a portion of the clamps as shown in Fig. 6.

Fig. 8 is a plan view of a complete corner post support that is employed to make the rack mobile, with parts broken away.

Referring to the drawings, the shelf rack as shown in Fig. 1 comprises a series of five shelves 1, 2, 3, 4 and 5 which are supported by the four angle corner post members 6, 7, 8, and 9. Each pair of post members 6—7 and 8—9 is supported by the foot members 10 and 11.

Each shelf is supported by a frame member as indicated in Fig. 2 at 12 which comprises a rectangular frame made of channel members having inturned flanges as shown at 13. The frame is constructed to have at each corner a depending leg which is indicated by the angles 14. Each leg is welded to the frame 12 and depends therebelow as shown for the purpose of being stepped into the spaced aligned brace members 15, 16, 17 and 18 of the angle post members 6 which are shown in Fig. 3. The series of braces 15 to 18, inclusive, on each leg member are matched with the corresponding brace member of each

2

other leg member and are attached at the same relative position on each post. It will be noted that the set of braces as indicated at 15 is relatively narrow in width, whereas each set as indicated at 16, 17 and 18 increases in width. This is to permit the post members 6 to 9 to provide shelves at predetermined spacing, the spacing being of uniform distance between adjacent shelves if the posts are inserted in the upright position as shown in Fig. 3. If, however, the posts are inverted and the legs 14 are stepped behind the braces, each of the shelf members will be spaced a greater distance apart although the spacing between each of the shelves will be uniform. This is an important object of this invention.

The brace members 15 to 18 are secured to each of the angle post members by any suitable means such as by welding and they comprise a strap that extends across the angle. The center of the strap may be provided with an internally threaded collar, as indicated at 20 in Fig. 4, for receiving the thumb screw member 21 for the purpose of screwing through the collar and against the inner face of the angle leg member 14 clamping the same in the angle of the post member 6. The clamping action of the thumb screw 21 against the center of the angle of the leg 14 properly centers the leg within the post and, thus, maintains the proper alignment of the rack parts. Again the brace member may be flexed somewhat by the pressure exerted on the clamping screw 21 bringing the flanges of the post toward one another which enables them to exert a pressure on the ends of the plates 22 as indicated at 23 in Fig. 1.

The flange of each corner post is of a width which is slightly greater than one-half the difference between the lengths of the frame and the plate, and the width of the plate is slightly greater than the width of the frame so that tightening the thumb screws 21 will draw the corner posts toward one another and force the edges of the corner post flanges into clamping engagement with the ends of the plates.

A single plate member 22 is shown in Fig. 5. This plate member has been slotted as indicated at 24 for the purpose of receiving trays. Each of the plate members 22 may be plain and, thus, provide a plain shelf rather than a slotted shelf for the purpose of receiving instruments, dishes or other similar articles. Each of the slots 24 is cut to a lower extent along one edge of the shelf, as indicated at 25, than on the other edge of the shelf, as indicated at 26 as shown in Fig. 6. The slots 24 are open as indicated on the right and are closed as indicated on the left of this view. The closed end of the slots functions as a stop for the tray members as indicated at 27.

Each of the plate members constituting the shelf has an inturned flange 28 on the front and rear thereof. It is preferable although not required to curve the sides of the plate edges as indicated at 30, but the same may be sharply broken if desired in which case the slot 26 would be substantially flush with the upper surface of the plate member to form a stop.

Each of the inturned front and rear flanges of the plate member is provided with an angle 31 which, as shown in Fig. 6, supports the plate member 22 on the upper surface of the frame member 12 and the inturned edges 28 of the plate member are close to each other and are substantially at the center of the channel members as shown. The angles 31 not only provide rigidity for the plate members 22 and a support therefor, but these angles also space the central panel of the plate member 22 from the upper and lower surfaces of the frame 12 as shown in Fig. 6; thus, allowing the tray members 27 to pass between the spaced slots and rest upon the top surface of the angles 31.

On the top surface of each frame a drip or condensation pan member 33 is supported which has a bowl portion 34 and an annular flange member 35 that rests on the inner edge of the inturned flanges 13 of the frame member 12 and is merely held in position by reason of the fact that the bowl 34 is confined between the inturned edges of the frame 12. However the drip trays 33 may be removed, if desired, through the ends of the rack as shown in Fig. 1 providing the flanges 35 of the pan are

not too wide to prevent their passage between each pair of posts 6 and 7 when tilted.

The underside of each frame 12 is likewise provided with one of the plate members 22 which is constructed identically with the plate member on the top thereof. Each side of the underside of the frame 12 is provided with a series of preferably four clamp members such as indicated at 36. Each clamp member which is also shown in Fig. 7 is provided with a finger control portion 38 and a body portion 39 with a pivot 40 on the bracket 41, the bracket 41 being welded to the lower flange 13. As shown in Fig. 7 the body portion 39 of the clamp is rectangular and, when moved to a position of 90° from that shown it will release the flange 31 of the plate 22. The pivot 40 is offset relative to the flange and thus supports the plate 22 of the underside of the frame 12.

By assembling each of the plate members 22 on a frame member 12 and placing a drip pan 33 therein, one may then assemble the same on the four posts 6, 7, 8 and 9. By stepping the legs 14 into position behind the brace members and by clamping each of the leg members 14 by the thumb screws 21 each shelf may be locked in place. Owing to the fact that the length of each plate 22 is slightly less than its frame, it becomes clamped in position by the legs of the posts when the thumb screws are tightly set. This is particularly true when the thumb screws cause the braces to bow the flanges of the posts and thus draw them tightly against the ends of the plates 22. Thus each of the plates is rigidly secured relative to the posts and relative to each other, and the trays may be inserted between the adjacent plates with their upper edges guided by a slot in the plate on the underside of the upper shelf member and the lower edge of the tray being guided by a corresponding slot in the lower plate on the shelf member, and the stops as indicated at 26 prevents the trays from being shoved clear through the shelf member.

The top of the rack may be provided with a plain shelf member, such as indicated by the plate 42, which need not be provided with the slots 24. It is also provided with smooth panel ends, such as indicated at 22a, each of which extends over the four corner posts and thus provides a neat finish on the upper end of the rack.

Each foot, as indicated at 10 and 11 in Fig. 1, is a duplicate of each other and extends materially beyond the pair of angular posts 6 and 7 to provide stability to the rack. Each foot is provided with a top panel 43 and a downwardly annular flange member 44 which form right angles at opposite ends of the foot as indicated at 45. A bracket member 46 is placed across each of the right angle corners, as indicated in Fig. 8, to receive the stem 47 of the caster member 48. Thus the caster members are placed at the opposite ends of each foot and one may stand on the extending portion of each foot to pull on the rack without fear of tilting and upsetting the same which is an important factor in a portable rack of this kind.

Each foot is provided with a pair of upwardly extending angles 50 which are spaced apart at the same distance as that of the pairs of posts 6-7 and 8-9. In order to assemble the rack on the feet 10 and 11, the angle posts are set down over the upwardly extending angle 50 with the braces confining the posts in place and then the frame of the bottom shelf is inserted in place inside the angle of the upwardly extending angle 50 placing the angle 50 between the corner posts 6 to 9 and the corresponding legs 14 of the lowermost frame 12. When the thumb screws 21 of the lowermost brackets are screwed inwardly, they engage the legs 14 and tightly clamp the upwardly extending angle 50 against the corner posts, thus securing the whole of the rack as one integral unit to the feet and permit the same to provide a mobile structure.

We claim:

1. A shelf rack comprising a plurality of rectangular frames, each frame having a downwardly extending leg at each corner, a plurality of matched plate members with inturned front and rear edges and of greater width and shorter length than said frames, one plate member resting on the top of each frame with the inturned front and rear edges closely adjacent the front and rear sides of the frame, four corner posts each having a plurality of matched braces attached in the same relative position along each post to provide a set of braces at different elevations for each shelf, each of said corner posts having a width slightly greater than one-half the difference

in the distance between the length of each frame and the length of each plate, said braces spaced outwardly from the posts to receive a leg of a frame stepped therebehind to support the frames, and a fastening means on each brace to clamp the leg against the post and rigidly hold all the parts together and to clamp and lock the plate ends between the posts at opposite ends of the rack.

5 2. A shelf rack comprising a plurality of rectangular frames, each frame having a downwardly extending leg at each corner, a plurality of matched plate members with inturned front and rear edges and of greater width and shorter length than said frames, one plate member resting on the top of each frame with the inturned front and rear edges closely adjacent the front and rear sides of the frame, four corner posts each having a plurality of matched braces attached in the same relative position along each post to provide a set of braces at different elevations for each shelf, each of said corner posts having a width slightly greater than one-half the difference in 10 the distance between the length of each frame and the length of each plate, said braces spaced outwardly from the posts to receive a leg of a frame stepped therebehind to support the frames, a fastening means on each brace to clamp the leg against the post and rigidly hold all 15 the parts together and to clamp and lock the plate ends between the posts at opposite ends of the rack, and a foot for each pair of corner posts having a pair of spaced upwardly extending projections to be received and clamped with the legs of the lowermost frame for anchoring the 20 posts to said foot, said feet extending beyond the corner posts to provide stability to the rack.

25 3. A shelf rack comprising a plurality of rectangular frames, each frame having a downwardly extending leg at each corner, a plurality of matched plate members with inturned front and rear edges and of greater width and shorter length than said frames, one plate member resting on the top of each frame with the inturned front and rear edges closely adjacent the front and rear sides of the frame, four corner posts each having a plurality of matched braces attached in the same relative position along each post to provide a set of braces at different elevations for each shelf, each of said corner posts having a width slightly greater than one-half the difference in 30 the distance between the length of each frame and the length of each plate, said braces spaced outwardly from the posts to receive a leg of a frame stepped therebehind to support the frames, the braces of consecutive sets being of different widths and the spacing between their corresponding top and bottom edges being selected to provide different dimensions between shelves when the four corner posts are inverted, and a fastening means on each brace to clamp the leg against the post and rigidly hold all the parts together and to clamp and lock the plate ends between the posts at opposite ends of the rack.

35 4. A shelf rack comprising a plurality of rectangular frames, each frame having a downwardly extending leg at each corner, a plurality of matched plate members with inturned front and rear edges and of greater width and shorter length than said frames, one plate member resting on the top and another removably held to the bottom of each frame with the inturned front and rear edges closely adjacent the front and rear sides of the frame, four corner posts each having a plurality of matched braces attached in the same relative position along each post to provide a set of braces at different elevations for each shelf, each of said corner posts having a width slightly greater than one-half the difference in 40 the distance between the length of each frame and the length of each plate, said braces spaced outwardly from the posts to receive a leg of a frame stepped therebehind to support the frames, and a fastening means on each brace to clamp the leg against the post and rigidly hold all the parts together and to clamp and lock the top and bottom plate ends between the posts at opposite ends of the rack.

45 5. A shelf rack comprising a plurality of rectangular frames, each frame having a downwardly extending leg at each corner, a plurality of matched plate members with inturned front and rear edges and of greater width and shorter length than said frames, one plate member resting on the top and another removably held to the bottom of each frame with the inturned front and rear edges closely adjacent the front and rear sides of the frame, an angle spaced inwardly of each inturned edge 50 of each plate to space the underside of each plate from

said frame, four corner posts each having a plurality of matched braces attached in the same relative position along each post to provide a set of braces at different elevations for each shelf, each of said corner posts having a width slightly greater than one-half the difference in the distance between the length of each frame and the length of each plate, said braces spaced outwardly from the posts to receive a leg of a frame stepped therebehind to support the frames, and a fastening means on each brace to clamp the leg against the post and rigidly hold all the parts together and to clamp and lock the top and bottom plate ends between the posts at opposite ends of the rack.

6. A shelf rack comprising a plurality of rectangular frames, each frame having a downwardly extending leg at each corner, a plurality of matched plate members with inturned front and rear edges and of greater width and shorter length than said frames and each having a series of aligned transverse slots in the adjacent plates to form guides, one plate member resting on the top and another removably held to the bottom of each frame with the inturned front and rear edges closely adjacent the front and rear sides of the frame, an angle spaced inwardly of each inturned edge of each plate to space the underside of each plate from said frame, a drip pan resting on the top of each frame under the slotted top plate thereof, four corner posts each having a plurality of matched braces attached in the same relative position along each post to provide a set of braces at different elevations for each shelf, each of said corner posts having a width slightly greater than one-half the difference in the distance between the length of each frame and the length of each plate, said braces spaced outwardly from the posts to receive a leg of a frame stepped therebehind to support the frames, and a fastening means on each brace to clamp the leg against the post and rigidly hold all the parts together and to clamp and lock the plate ends and the drip pan ends between the posts at opposite ends of the rack.

7. A shelf rack comprising a plurality of rectangular frames, each corner of said frame having an inwardly

facing downwardly extending angle to form a leg, a plurality of matched plate members with inturned front and rear edges and of greater width and shorter length than said frames, one plate member resting on the top of each frame with the inturned front and rear edges closely adjacent the front and rear sides of the frames, four corner posts each being angular in cross section and having a plurality of matched braces extending across the angle and attached in the same relative position along each post to provide a set of braces at different elevations for each shelf, each of said corner posts having a width slightly greater than one-half the difference in the distance between the length of each frame and the length of each plate, said braces receiving the angle legs stepped therebehind to support the frames, and a thumb screw carried by each brace to engage and clamp the surface of the angle leg nested against the angle post and to clamp and lock the plate ends between the posts at opposite ends of the rack.

8. A shelf rack corner post comprising an angle having outwardly projecting flanges, a series of spaced braces connecting said flanges, said braces being progressively wider from one end of the post and their spacing from each other being selected to provide two different sets of uniform distances, one set between the tops of adjacent braces and the other set between the bottoms of adjacent braces.
